IRONING BOARD HOLDER

William G. Michel, Three Rivers, Mich.

Application April 10, 1950, Serial No. 155,007

2 Claims. (Cl. 248—309)

1

This invention relates to improved apparatus for holding an ironing board in place on a door, wall, or other vertical surface.

Many people like a portable ironing board so that they can iron in any room in the house as necessity may require, or in any location in a room that is most convenient or desirable. Some people use the built-in types of ironing board because the room was constructed with it originally. Others modernize their homes and when they decide upon the most desirable place to iron will have a collapsible ironing board either built into a closet for concealing it when not in use, or hinged to a door or wall, or other vertical surface.

The apparatus of this invention, however, is of particular advantage to the great majority of housewives who will always prefer to do their ironing at the most convenient and desirable location in a room that they will prefer to work in at the time they have ironing to do. When they have finished ironing they will want to collapse the legs to the ironing board and store it out of the way and perhaps out of sight. A customary location is on the back of a door which is closed most of the time or opened back against a wall, or other vertical surface most of the time. By using the apparatus of this invention no floor space is occupied and when fastened to the back of a door the ironing board can be stored out of sight.

Specifically the apparatus of this invention comprises an assembly of three channel pieces of metal, one of which is slightly larger than the other two so that one end of each of the other two channels can nest into the central channel, the central channel having screw holes punched near each end while the other two channels have screw holes punched at regular intervals along their entire length, means for fastening the two similar channels at their far ends to a flat surface, means for fastening the same two channels along their inner ends to the third or central channel, a chain secured to one of said latter fastening means and suspended on the other fastening means by a split ring, and bracket means separated from the aforesaid apparatus and below it for supporting an ironing board.

The features and details of the apparatus of this invention can be more readily understood from a description of the accompanying drawing which is a part of this application. The drawing shows three different views of an ironing board held in place on the back of a panelled door, by the apparatus of this invention, and also en-

2

largements of the means for fastening the channel pieces together and holding the chain.

The invention consists in the novel features of construction and combination of parts herein-after described and set forth, reference being had to the accompanying drawing in which—

Fig. 1 shows an ironing board with its legs collapsed, held firmly by the apparatus of this invention to the back of a door with a center panel. Fig. 2 is a side view of the same door with the ironing board held firmly in place by the device of this invention.

Fig. 3 is a sectional view looking down at the device of this invention from a plane through the door and upper end of the ironing board along line 3—3 in Fig. 1.

Fig. 4 is a vertical sectional view through the nested channels along the line 4—4 in Fig. 1.

Fig. 5 is a vertical sectional view through the nested channels along the line 5—5 in Fig. 1.

In Fig. 1 of the drawing a door 6 is outlined and shows the central panel 7 with an ironing board 8 also outlined and held in place by the apparatus of this invention. The ironing board is supported up off the floor by brackets 9, which are fastened to the bottom or kick-board of the door. The similar metal channel pieces 10 and 11 are fastened at opposite ends as shown to the stiles of the door by wood screws. The central metal channel 12 is slightly larger than channels 10 and 11 so that it fits over the channels 10 and 11. It is fastened to the inside end of channel piece 10 by an open eye or hook bolt 13, while the other end is fastened to the inside end of channel piece 11 by a closed eye bolt 14. A chain 15 is secured to the eye bolt 14 and has a split ring 16 which may be attached to any link of the chain and then hooked onto the open eye bolt 13.

The side view of the door and ironing board shown in Fig. 2 reveals, when the legs of the ironing board are folded flat against the board, how the ironing board is compactly and closely held parallel to the door by the apparatus of this invention. From this side view it is very apparent that in storing the ironing board in this manner up off the floor the board and its usual covering will remain clean longer, as well as the floor. This view also shows how the metal channels hold the ironing board out from the door so as to not mark the door.

In the enlarged sectional plan view of Fig. 3 the use of chain 15 to hold the ironing board relatively tight is clearly shown. The chain prevents the ironing board falling away from the door as

well as rocking parallel to the door. Especially, when the ironing board is stored on the back of a door will there be a pronounced tendency for the ironing board to swing about when the door is suddenly jerked open or shut. This figure of the drawing also shows clearly the way the ironing board is held flat against the metal channels and not up against the door, thus reducing any tendency for making noise or damaging the door by knocking against it. The view also shows the adaptability of the device to doors with or without center panels. The three metal channels are assembled so as to provide continuous straight line contacts with a flat door surface (not shown) or a strong straight metal brace from stile to stile of the door while out of contact with the intermediate panel of the door as shown by the space 17 in Fig. 3.

In Fig. 4 which is an enlarged vertical sectional view, the detail of the nested channels and the open eye or hook bolt 13, which receives the split ring 16 of chain 15 is clearly shown. An hexagonal nut 18 is used on the hook bolt at the outside face of the central metal channel 12, while a square nut 19 is fitted inside the smaller metal channel 10 and the hook bolt screwed into it. This arrangement of a square nut locked by the walls of the inner channel 10 is convenient once the apparatus is installed because if the hook bolt should become loose it is only necessary to tighten the hexagonal nut on the outside.

Fig. 5 is an enlarged vertical sectional view through the smaller channel 11 which shows the detail of the closed eye bolt 14 with a hexagonal nut 20 at the outside face of central metal channel 12 and a square nut 21 fitted inside smaller nested channel 11 to receive the eye bolt 14 when the device of this invention is assembled and installed.

From the foregoing description it is readily apparent that the apparatus of this invention may be installed on either the usual panel type of door, or the door with an unbroken flat surface, or on any flat wall surface. It is equally applicable to either wooden or metal doors. This is because of the use of metal channel pieces 10, 11 and 12 which are preferably made out of aluminum or some other light weight relatively low cost material. It is also a feature of the smaller channel pieces 10 and 11 that one end of each be closed with a metal return to touch the door and strengthen the channel when the holding screws are tightened into the door stiles. The inside ends of the smaller channels may also have metal returns to strengthen the channels when up against a flat surface instead of a panel door.

The use of three channels as described makes the device applicable to almost any size door, especially those having central panels. When the span across the central panel is relatively great the three channels can be strengthened across the span by inserting a couple of plain bolts 22 and 23 equally spaced from the center of the central channel 12 through the inside ends of the smaller channels 10 and 11 respectively, and fastening them with square nuts on the inside of the small channels as previously described in connection with the open and closed eye bolts.

The feature of this apparatus is the use of the channel pieces which when connected through their extreme bolt holes will as presently being

made properly span a panel door 36 inches wide. The same three channel pieces can be also fitted closely together, using other bolt holes so as to span a panel door 24 inches wide. At the same time they can be applied to any width of a continuously flat surface. And the open eye and closed eye bolts need only be separated from each other along the channel pieces far enough to accommodate the width of the ironing board where it rests against the bolted channel pieces, so as to suspend only sufficient length of chain to fit snugly around the end of the ironing board.

Because it is an object of this invention to hold the ironing board firmly the chain 15 must have means for adjusting its length. The split ring serves two purposes: first, it may be connected to any link of the chain so as to provide any required length of chain to circle around any size of ironing board including the padding usually attached to ironing boards; second, it is larger than a link of the chain so as to make it relatively easy to fasten the chain in place when the fit is close and when the operator is limited to the use of an inconvenient hand.

What I claim is:

1. A device of the class described comprising two similar metal channel pieces with holes punched therein at regular intervals along their entire length, a slightly larger metal channel with a plurality of holes punched near each end that can slide over the aforesaid two similar channel pieces, means for fastening said larger channel to one of said smaller channels through concentric holes comprising a bolt secured in place by an hexagonal nut on the outside of said channels and a square nut on the inside of the one smaller channel, means for fastening said larger channel to the other smaller channel through concentric holes similarly as aforesaid, both said fastening means holding a collapsible metal means of adjustable length for encircling one end of an ironing board.

2. A device of the character described comprising a chain with a split ring attached near one end and permanently attached to a closed eye bolt at the other end, said eye bolt extending through a hole near one end of a central metal channel piece and through a corresponding hole in another metal channel piece small enough to nest in said central metal channel piece, said smaller channel piece having means at the outer end for attaching same to a flat surface, said split ring being hooked onto an open eye bolt which extends through a hole near the other end of said central metal channel piece and through a corresponding hole in a third metal channel piece also small enough to nest in said central channel, said latter smaller channel also having means at its outer end for attaching same to a flat surface said central metal channel having a plurality of uniformly spaced holes at each end and said smaller metal channels having uniformly spaced holes along their entire lengths.
